DYNAMIC ELECTRON BEAM CONTROL SYSTEMS

Richard W. Sonnenfeldt, Haddonfield, N. J., assignor to
Radio Corporation of America, a corporation of Delaware

Application March 31, 1953, Serial No. 345,893

9 Claims. (Cl. 315—13)

This invention relates to systems for controlling the electron beams of cathode ray tubes and in more particularity, although not necessarily exclusively, to improved means for permitting the dynamic control of a plurality of electron beam components as employed in cathode ray tubes so as to maintain good focusing of the respective beam components and also to effect convergence of said components at all points of a raster scanned in a predetermined plane.

The present trend in television kinescopes is toward the use of flatter luminescent screens of increasingly greater areas. Also, the tendency is to shorten the tubes as much as possible to permit their employment in home instrument cabinets of smaller size. These factors make the problem of deflecting an electron beam or a plurality of electron beam components within the cathode ray tube a more difficult one. Deflection problems become even more complex when the size of the kinescope is increased along with the provision of specialized tube geometries aimed at enhancing the electron beam focus over the wide angles of deflection required in shorter tubes of large screen area.

A representative example of a cathode ray tube of the character referred to is a multicolor kinescope forming the subject matter of a U. S. Patent of Alfred N. Goldsmith, No. 2,630,542, issued March 3, 1953, and entitled "Multicolor Television." The luminescent screen of this tube consists of a multiplicity of phosphor areas of sub-elemental dimensions. Different sub-elemental areas are respectively capable of producing a color of light corresponding to a different one of three component image colors, when excited by electron beam energy. In this tube the different light producing phosphor screen areas are excited respectively by a plurality of electron beams approaching the screen from different angles through an apertured masking electrode. Color selection is secured by controlling the angle at which the electron beams approach the screen.

Another representative example of the cathode ray tube to which the present invention may usefully apply, forms the subject matter of a copending U. S. patent application of Russell R. Law, Serial No. 130,195, filed November 30, 1949, and entitled "Color Television Reproducing Tubes," now abandoned but continued in part by U. S. patent application, S. N. 165,552, filed June 1, 1950, entitled "Color Television." In general, the Law tube is similar to the Goldsmith tube. The chief difference is that the Law tube employs a single electron gun by which to produce the plurality of electron beam components, whereas, in the Goldsmith tube, an electron gun is provided to produce each beam. This is accomplished by imparting a spinning type of movement to the beam so that it is made to rotate about the central or longitudinal axis of the tube. In its rotation about the tube axis, the beam occupies at successive intervals, substantially the same positions as the different electron beams of the Goldsmith tube.

The expression "electron beam components," as used

2

in this specification and claims, is intended to cover the type of phosphor exciting electronic energy produced by a single or plurality of electron guns. This energy may be continuous or pulsating as required without departing from the spirit and scope of the present invention.

In the operation of multicolor kinescopes of the type referred to above, it is required that the plurality of electron beam components be made to converge substantially in the plane of the masking electrode of all points in the scanned raster. In view of the fact that the different points of the target electrode are at different distances from the point or region of the electron beam deflection it is necessary to provide a field producing means which is variably energized to produce a dynamic convergence control. One such electron beam control system forms the subject matter of a copending U. S. patent application of Albert Friend, Serial No. 164,444, filed May 26, 1950, and entitled "Electron Beam Controlling Systems." In the Friend case, an electron optical system is variably energized as functions of both the horizontal and vertical beam deflections. It can be demonstrated that without dynamic convergence control the electron beam components converge at different points as they are deflected to scan a raster. Locus of these convergence points is approximately parabolic in form. Accordingly as disclosed in the Friend application referred to, the electron optical system is variably energized as a parabolic function of both the horizontal and vertical beam deflection waveforms.

It has also been found that in wide angle cathode ray beam deflection systems the electron beam components tend to become defocused for the same reasons that a plurality of discrete electron beams tend to diverge when an attempt was made to converge them on a single point in the target plane. The electron beam convergence problem and the electron beam focusing problem in wide angle deflection systems are respectively discussed in U. S. patent application by Loren R. Kirkwood, entitled "Dynamic Electron Beam Control Systems," filed November 30, 1950, Serial No. 198,313, issued August 24, 1954, as Patent No. 2,687,493. A complete color television receiving system using a parabolic waveform for both beam convergence and beam focus correction in a multigun color kinescope, is described in an article entitled "Compatible Color TV Receiver," by Kenneth E. Kerr, appearing in the January 1953 issue of Electronics, page 98.

In the Kirkwood case and the Electronics article, it is pointed out that the electrical waveform required for electron beam convergence correction as well as focus correction are substantially the same. Accordingly, throughout the specification the terms "correction signal" or "correction waveform" will be meant to include the use of a parabolic form of electrical signal to improve the dynamic beam convergence and/or dynamic beam focus in a cathode ray beam system.

The obtaining of truly parabolic waveforms of suitable amplitude for the correction of dynamic beam convergence and focus, without resorting to costly circuitry and apparatus, has presented itself as a major problem. Ideally, the beam convergence and beam focus correction waveform should be obtained directly from the cathode ray tube in which beam convergence and beam focus correction is to be carried out. This is true since practice has shown that the amplitude of correction waveform required for convergence and focus correction in any given system is directly related to the amplitude of the beam deflection. Thus, if the correction waveform can be directly derived from those deflection circuits producing the basic beam deflection in the cathode ray beam device, aging of elements in the deflection circuits as well as long time

changes in the values of circuit parameters can be met by complementary and corresponding change in the amplitude of correction waveform. As one attempts to extract energy from a deflection circuit in a parabolic waveform, it is generally found that either linearity and circuit efficiency of the deflection system must be sacrificed or the correction waveform must suffer compromise in not representing a true mathematical parabola.

It is, therefore, an object of the present invention to provide an improved and simplified electron beam control system by which it is possible to maintain uniformity of performance in beam deflection within a cathode ray type tube.

It is further an object of the present invention to provide an improved generator circuit of electrical waves of complex waveform and high amplitude at a minimum of circuit complexity and expense.

It is still another object of the present invention to provide an improved and simplified means for deriving parabolic shaped waveforms suitable for cathode ray beam convergence and focus correction from standard forms of cathode ray beam deflection circuits.

It is a further object of the present invention to provide an improved and simplified means for deriving a parabolic shaped waveform of high voltage amplitude from a vertical electromagnetic cathode ray deflection circuit of the type used in home instrument television receivers.

Another object of the present invention is to provide an improved means for obtaining proper energization of the beam convergence and focus correction means of a multigun cathode ray beam color kinescope.

In the realization of the above objects and features of advantage, the present invention in one of its more specific embodiments, contemplates the development of a parabolic waveform by the addition of two signal waveforms derived from a conventional type cathode ray beam deflection circuit. Firstly, a substantially parabolic waveform is extracted from the deflection circuit in such a way that the low frequency components requisite to form a perfect parabola are absent. Secondly, a sawtooth waveform of voltage is developed which is conditionally added to the firstly developed signal to produce an overall waveform having substantially perfect parabolic features.

In the application of the present invention to a vertical type cathode ray beam deflection circuit which employs a standard vertical deflection output transformer, an additional transformer is provided having its primary winding connected in series with the primary winding of the vertical deflection output transformer. The secondary winding of the additional transformer is terminated in a resistance-capacitance load suited for the development of a high potential signal which approaches a parabolic waveform but is deficient in low frequency components. An auxiliary winding is then provided on the vertical deflection output transformer which is resistively terminated so as to form a voltage waveform corresponding to the developed sawtooth of a deflection current. This waveform is added to the firstly developed semi-parabolic waveform to provide the desired convergence and focus correction signals.

A more complete understanding of the present invention, as well as other objects and features of advantage thereof, will be gleaned from a reading of the following specification, especially when taken in connection with the accompanying drawings, in which:

Figure 1 is a combination block and schematic representation of one form of cathode ray beam system of the color kinescope variety with which the present invention may advantageously be employed.

Figure 2 is a combination block and schematic representation of one form of vertical deflection circuit embodying the present invention whereby to make available a focus and convergence correction waveform for use in a cathode ray beam deflection system.

Turning now to Figure 1, there is shown in block form

the basic elements of a dot multiplex type color television system to which the present invention may be advantageously applied. The underlying principles of operation of the dot sequential color television system are treated at some length in an article entitled "Analysis of dot sequential color television," appearing in the October 1951, issue of the Proceedings of the Institute of Radio Engineers, page 1280.

In the arrangement of Figure 1, a television signal receiving means is indicated by block 2. The television receiver amplifies signals detected by the antenna 4, demodulates these signals and provides a video signal to the video signal channel means indicated by block 6. Suitable color demodulation means are provided in the video signal channel 6 so that three separate component color signals are made available on the output buses 8, 10 and 12 respectively connected with gun control electrodes 14, 16 and 18. Average brightness information for each color channel is developed by the D. C. restorer circuit 20. The restorer circuit 20 is a three channel device which permits separate brightness information to be applied to the separate electron gun cathodes 22, 24 and 26.

As described in an article entitled "A three gun shadow mask color kinescope," by H. B. Law, appearing in October 1951, issue of the Proceedings of the Institute of Radio Engineers, pages 1186-1194, the color television picture reproducing kinescope 28, referred to sometimes as a "Triniscopic," includes three separate cathode ray beam gun structures. The gun control electrode and cathodes of these gun structures have been described hereinabove. Also shown within the envelope 28 are the respective gun screen electrodes 30, 32 and 34. The gun screen electrodes are connected in a conventional fashion to a source of positive power supply potential indicated by the block 36. Focus control electrodes are indicated at 38, 40 and 42 for focusing the respective electron beams onto the multicolor phosphor dot target 44. A shadow mask for producing selective energization of predetermined color dots by the respective electron beams is indicated at 46. For purposes of illustration, the direction of approach to the target of the three electron beams produced by the three electron beam guns, is indicated by the dotted lines 50, 52 and 54. Thus, as described in the above article, "A three gun shadow mask color kinescope," the three beams produced by the respective electron guns passing through a given aperture in the shadow mask 46, will excite respective deposits of phosphor on the target 44. The phosphor deposits on the target 44 are arranged in tangential relationship so that any group of three deposits served by a given aperture in the shadow mask 46, will, when simultaneously excited by properly balanced beam energy, act to produce a resultant white light. A beam convergence electrode 55 is provided for insuring the coincidence of the three beams upon any given aperture in the shadow mask 46 for any angle of beam deflection.

The method by which the beam convergence electrode serves to improve coincidence of the three electron rays produced by the three separate electron beam guns is discussed in an article, "Deflection and convergence in color kinescopes," by Albert W. Friend, appearing in the Proceedings of the Institute of Radio Engineers for October 1951, pages 1249-1263. In this article is pointed out that in order to accomplish a satisfactory degree of beam convergence over very wide angles of deflection, the waveform of voltage applied to the beam convergence electrode 55 should be substantially parabolic in shape, and synchronously related to the deflection signal of the system. As brought out in the above identified U. S. patent application "Dynamic Electron Beam Control Systems," filed November 30, 1950, Serial No. 198,313, by Loren R. Kirkwood, issued August 24, 1954, as Patent 2,687,493, the dynamic beam convergence signal applied to the beam convergence electrode 55 may also be applied to the gun focus electrodes 38, 40 and 42 to improve the

uniformity of focus of each of the beams over the area of the target 44. It is with the production or generation of the required parabolic waveform for use as a beam convergence electrode or for use as a beam convergence signal or gun focus control signal, that the present invention is concerned.

The general method of generating the required parabolic waveform and applying the resulting waveform as a correction signal to the beam convergence electrode and gun focus electrodes of a color triniscopic, is illustrated in Figure 1. Demodulated video signal developed by the television receiver 2 is also applied to a sync signal separator 56. Circuits of this type are well known in the art and act in such a way as to separate the synchronizing component from the composite video signal as demodulated by the television receiver 2. Separated horizontal synchronizing signal may then appear on bus 58 while vertical synchronizing signal may appear on bus 60. These synchronizing signal buses are respectively connected with the input circuits of the horizontal and vertical deflection wave generators 62 and 64. The deflection wave generators 62 and 64 may be of conventional form. Horizontal deflection signal is developed across the output terminals 66 and 68 of the horizontal deflection wave generator. The output terminals 66 and 68 are connected with the horizontal deflection winding of the deflection yoke 70 surrounding the neck of the triniscopic 28. Output terminals 72 and 74 for the vertical deflection wave generator 64 are correspondingly connected with the vertical deflection winding of the beam deflection yoke 70. Horizontal deflection wave energy is extracted from the horizontal deflection wave generator 62 and applied to a horizontal convergency control wave generator 76 which is designated as having a high impedance. The parabolic control wave for horizontal beam convergence and focus correction, therefore, will appear across the terminals 78 and 80 of the control wave generator 76. A corresponding control wave generator 82 is provided for excitation from the vertical deflection wave generator 64. The required parabolic control waveform developed by the vertical convergence and focus control wave generator will, therefore, appear across terminals 84 and 86 thereof. As shown in the drawing, the parabolic control waveform output signals of the horizontal and vertical convergence and focus control wave generators are serially added with one another to provide a composite waveform which may be applied to the beam convergence electrode 55. As shown in the drawing, the terminal 86 of the vertical convergence focus control wave generator is grounded while the terminal 78 of the horizontal convergence and focus control wave generator is capacitively coupled, via capacitor 88, to the beam convergence electrode 55. A high potential static convergence supply voltage is provided by the voltage producing means 90. One terminal of the supply voltage means 90 is grounded while the other terminal is connected through a high resistance 92 to the beam convergence electrode 55. Thus, the composite parabolic convergence and focus control wave will be superimposed upon the static potential developed by the supply voltage means 90.

In order to provide dynamic focus correction of the electron beams produced by the electron ray guns within the triniscopic 28, a voltage dividing means 94 is connected across the terminal 78 to ground. A variable tap 96 on the resistance element 94 permits any voltage level of composite horizontal and vertical convergence and focus control wave to be obtained. This reduced amplitude version of the composite control wave is coupled via capacitor 98 to the gun focus electrodes 38, 40 and 42, as described in the above Kirkwood patent application. Static focus supply voltage is supplied by the voltage supply means 100 having one terminal grounded and its positive terminal connected through a relatively high value resistor 102 to the gun focus electrodes.

It is noted that since the vertical convergence and focus

control waveform generator is productive of a lower frequency parabolic voltage than the horizontal convergence focus control wave generator that it has one of its terminals connected with ground potential as shown at terminal 86. This prevents the possible attenuation of the higher frequency components of the horizontal convergence and focus control waveform generator from being dissipated in the circuit capacitance of the vertical convergence focus control waveform generator, as would be the case were the horizontal control waveform generator placed at ground potential instead of the vertical generator.

All of the above description of the arrangement of Figure 1 has been in an attempt to lay or establish a better understanding of the problems which are seen to be solved by the present invention. The present invention concerns itself more directly with improved means for accomplishing the generation of a vertical convergence and focus control waveform and hence is directed to a general form of improved circuitry, which in essence combines the functions of blocks 64 and 82 in Figure 1, that is, it incorporates in a single circuit a vertical deflection waveform generator action, as well as a vertical convergence and focus control waveform generator action.

One embodiment of the present invention is shown in Figure 2. In Figure 2 it will be assumed that a sawtooth deflection waveform of suitable linearity for cathode ray beam deflection purposes is available across terminals 110 and 112. The sawtooth waveform 114 appearing across these terminals is capacitively coupled via capacitor 116 to the control electrode 118 of a pentode type vacuum tube amplifier 120. It will be appreciated that the merits of the present invention are in no way limited to the particular form of vacuum tube employed. Where a pentode amplifier is used a screen biasing potential should be applied to the screen electrode 122 from a source of positive power supply potential 124 through a dropping resistor 126. A conventional screen electrode bypass capacitor 128 is connected from the screen electrode 122 to circuit ground. A cathode biasing resistor 132 shunted by cathode bypass capacitor 134 is connected in the conventional manner between the cathode 136 and circuit ground. A conventional grid leak current resistor 138 is connected between the control electrode 118 and circuit ground. In accordance with the present invention, the anode circuit of the amplifier 120 includes a number of transformer instrumentalities other than the conventional vertical deflection transformer. Anode biasing potential for the amplifier 120 is supplied from the positive power supply terminal 140 through the primary windings 142 and 144 of transformer means 146 and 148. A conventional deflection yoke driving secondary winding 149 is associated with the transformer means 146 for driving the deflection yoke 150 surrounding the neck of the kinescope 152.

For purposes of simplicity the kinescope 152 has been illustrated as being of the single electron gun type and the parabolic waveform developed by the novel circuitry of the present invention will be applied for achieving dynamic focus control only. It will be appreciated, however, in the reference to Figure 1 and the description thereof, that the circuitry of Figure 2 is equally applicable to a multigun kinescope such as 28 in Figure 1 to also accomplish dynamic beam convergence correction.

In order to develop a parabolic control waveform in accordance with the present invention, two signal components are added with one another. The first signal component is developed across the secondary winding 153 of the transformer means 148. The capacitor 154 is placed in shunt with the winding 153 and so chosen as to resonate the secondary winding 153 at a frequency below the vertical deflection frequency. A variable tapped resistor 156 is connected across the capacitor 154 so as to permit the selection of any portion of the voltage amplitude appearing across the secondary winding 153. Due

to inherent characteristics of most commercially available transformers, the lower frequency components of the sawtooth current flowing through the primary winding 144 of the transformer means 148 will not find representation in the secondary winding 153. Characteristics of the transformer means 148 will not only impose a loss in low frequency components, but also produce a net shift in the phase of the signal appearing across resistor 156 relative to the beginning and ending of the sawtooth current waveform flowing in the primary circuit. Thus, the signal appearing across resistor 156 will be the result of removing the lower frequency components from a parabolic waveform signal.

In accordance with the present invention, the absence of lower frequency components and the resultant phase shift in the signal appearing across resistor 156 is compensated by the addition of a sawtooth waveform developed across the resistor 158. Resistor 158 is connected in shunt with the secondary winding 160 of transformer means 146. A tap 162 on the winding 160 is connected with circuit ground. The sawtooth of current developed in the secondary winding 160, will, therefore, cause a sawtooth voltage to appear across resistor 158 in such a way that the tap 166 on resistor 158 may be positioned to display substantially no voltage with respect to ground or it may be adjusted to display a positive or negative going sawtooth voltage waveform of an adjustable amplitude. Depending upon the particular characteristics of the transformer 148, it is found in the practice of the present invention that the tap 166 may be so adjusted that when taken in combination with the voltage developed across resistor 156 a substantially perfect parabola of voltage will appear at terminal 168. This terminal is then capacitively coupled by a capacitor 170 to a focus electrode 172 of the kinescope 152. The static focus supply voltage means 174 has its negative polarity terminal connected with circuit ground and its positive polarity terminal connected through an isolating resistor 176 to the focus electrode 172. The value of the resistor 176 is so chosen as to allow a sufficient amplitude of dynamic focus control voltage to be developed at the focus electrode by merit of its coupling via capacitor 170 to the parabolic control voltage appearing at terminal 168.

It will be appreciated that the practice of the present invention is in no way limited to the provision of two separate transformer means. It is evidently quite possible to provide a single transformer means having three secondary windings or three separate transformer means, each having a single secondary winding. In one of the preferred form of the invention, the arrangement of Figure 2 is desirable since by providing a separate transformer means 148, the primary winding 144 may be resonated by capacitor 178 to supplement the resonant secondary winding 153. In this way, the deflection current waveform delivered to the deflection yoke 150 is not altered by any circuit change in either the primary or secondary windings of the transformer means 148.

For purposes of considering the application of the embodiment of the present invention in Figure 2, to the circuitry of Figure 1, it is only necessary to regard the output terminal 84 of the vertical convergence control wave generator 82 of Figure 1, as the equivalent of terminal 168 in Figure 2. The horizontal convergence and focus control generator 76, illustrated in both Figures 1 and 2, merely provides the means for accomplishing the serial addition of a parabola of horizontal deflection frequency to the vertical deflection frequency parabola developed by the circuitry of the present invention.

What is claimed is:

1. In a voltage generating means for developing a substantially parabolic waveform, the combination of: a source of sawtooth waveform; integrating means including low frequency attenuation means coupled with said sawtooth waveform source for developing an integrated signal waveform; means coupled with said sawtooth wave-

form source for developing a sawtooth waveform suitable for addition to the waveform produced by said integrating means including said low frequency attenuation means; circuit means connected with said integrating means including said low frequency attenuation means and said sawtooth waveform developing means for linearly combining the output signals from each to provide a single composite waveform of substantially parabolic shape.

2. A signal waveform system for developing a substantially parabolic waveform signal comprising in combination: a source of sawtooth deflection signal; a signal amplifier tube having at least an anode and control electrode; signal coupling means connected from said sawtooth deflection signal source and said control electrode; a source of biasing potential for said anode; transformer means having a primary winding connected between said anode and said source of biasing potential; a first secondary winding and a second secondary winding included in said transformer means, said first secondary winding having a predetermined inductance; a capacitor connected in shunt with said first secondary winding means to form a tuned circuit whose resonance is below the recurrence frequency of sawtooth signal supplied by said sawtooth signal source; resistance means connected in shunt with said second secondary winding; and a connection from a point on said resistance means to said first secondary winding.

3. A signal waveform system according to claim 2, wherein there exists a predetermined leakage inductance between said secondary means and said transformer primary means and wherein there is additionally provided a capacitor in shunt with at least a portion of said transformer primary winding means, the value of said capacitor being so chosen as to resonate with the value of leakage inductance at a frequency sufficiently low to minimize leakage inductance ringing in said first secondary winding.

4. In a parabolic wave generating system, the combination of: an output transformer means having a primary winding; a first secondary winding and a second secondary winding; an auxiliary transformer means having a primary winding and a secondary winding; an inductive load connected across said output transformer first secondary winding; an electron discharge tube having at least an anode and control electrode; a source of biasing potential for said anode; connections between said anode, said auxiliary transformer means primary winding, said output transformer means primary winding and said source of biasing potential for placing said primary windings in series with one another between said anode and said biasing potential source; a source of driving signal for said electron discharge tube, said driving signal having a waveform of such contour that when amplified by said discharge device results in a substantially linear sawtooth current flow through said inductive load; resistance means connected in shunt with said output transformer means secondary winding; a capacitor connected in shunt with said auxiliary transformer means secondary winding and a connection between said resistance means and said auxiliary transformer means secondary winding such that the voltage appearing between a point on said auxiliary transformer secondary winding and a point on said output transformer second secondary winding is substantially parabolic in wave shape.

5. In a parabolic wave generating system, according to claim 4, wherein said auxiliary transformer means has an inherent leakage inductance between its primary and secondary windings and wherein there is additionally provided a capacitor connected in shunt with said auxiliary transformer means primary winding, the value of said capacitor being so chosen relative to the value of said leakage inductance as to minimize the effect of leakage inductance ringing in said auxiliary transformer means secondary winding.

6. In a parabolic wave generating system, according to claim 4, wherein said capacitor in shunt with said

auxiliary transformer means secondary winding is so chosen relative to the value of the inductance of said auxiliary transformer means secondary winding as to define a resonant circuit tuned to a frequency value below the recurrence frequency of the waveform applied to said electron discharge tube control electrode.

7. In a parabolic wave generating system, according to claim 6, wherein there is additionally provided a resistance means connected in shunt with said auxiliary transformer means secondary winding, said resistance means having a variable signal output tap thereon; and wherein the output transformer second secondary winding is provided with a tap which is established at a signal datum potential; and wherein said resistance means connected in shunt with said output transformer second secondary winding has a variable tap thereon; and wherein said connection from said output transformer resistance means auxiliary transformer means secondary winding is made from said variable tap on said output transformer resistance means.

8. In a cathode ray beam deflection system in which is to be developed a sawtooth of deflection current and a parabola of control voltage, said parabola of control voltage being suitable for dynamic beam convergence and dynamic beam focus control, the combination of: an electron discharge tube having at least an anode cathode and control electrode; input circuit means connected between said control electrode and said cathode for receiving a deflection signal; a first and a second transformer means whose primary windings are connected in series with one another between said electron discharge tube anode and cathode; a first secondary winding on said first transformer means designated for connection with an electromagnetic deflection yoke; a second secondary on said first transformer means having a tap thereon; a

signal datum terminal connected with said first transformer second secondary winding tap; a first resistance means connected in shunt with said first transformer second secondary winding, said first resistance means having a variable tap thereon; a secondary winding on said second transformer means having a predetermined inductance; a capacitor connected in shunt with said second transformer secondary winding, the value of said capacitor being so chosen as to resonate with the inductance of said second transformer secondary winding at a frequency below the recurrence rate of the deflection signal applied to said electron discharge tube control electrode; a second resistance means connected in shunt with said second transformer secondary winding, said second resistance means having a variable tap thereon whereby there is permitted to exist between said variable tap and said signal datum terminal a substantially parabolic waveform concomitantly with the existence of sawtooth current flow in said sawtooth transformer said secondary winding.

9. In a cathode ray beam deflection system according to claim 8, wherein said cathode ray beam deflection system is incorporated in a color television picture reproducing system employing a multi-element electron beam and having a beam convergence electrode and wherein said second transformer secondary winding is connected with said beam convergence electrode.
